a corporation of Missouri

Application January 22, 1947, Serial No. 136,285

Term of patent 3½ years

(Cl. D1—12)

To all whom it may concern:

Be it known that I, Henry A. Thuernau, a citizen of the United States, residing in the city of Clayton, county of St. Louis, and State of Missouri, have invented a new, original, and ornamental Design for an Outdoor Advertising Bulletin Board, of which the following is a specification, reference being had to the accompanying drawing, forming a part thereof.

In the drawing:

Fig. 1 is a front elevational view in perspective;
Fig. 2 is a top or plan view;
Fig. 3 is a front elevational view, and
Fig. 4 is an end elevational view, each view showing an outdoor advertising bulletin board of my novel design.

I claim:

The ornamental design for an outdoor advertising bulletin board, substantially as shown.

HENRY A. THUERNAU.
